Primary Examiner—Doris Clark

[**] Term: 14 Years

[57] CLAIM

[21] Appl. No.: 29,266

The ornamental design for a combined box girder and
beams with joint, as shown and described.

[22] Filed: Aug. 17, 1994

DESCRIPTION

[30] Foreign Application Priority Data

Feb. 25, 1994 [SE] Sweden 940448

[52] U.S. Cl. D25/126

[58] Field of Search D25/126, 128,
D25/61; 52/223.8, 223.9, 223.11-223.43,
650.1, 731.2, 731.3, 664

References Cited

FIG. 1 is a perspective view taken from the front upper left
and showing a combined box girder and beams with joint;
and,

FIG. 2 is a bottom view thereof.

The combined box girder and beams with joint is broken
away in the far end for indefiniteness of the article length.
